The ornamental design for an electrical switch, as shown and described.

DESCRIPTION

FIG. 1 is a front, left perspective view of a first and third embodiments of an electrical switch showing my new design;

FIG. 2 is an exploded, front, left perspective view of the first and third embodiments;

FIG. 3 is a top plan view of the first and third embodiments;

FIG. 4 is a top plan view of the separated upper assembly of the first and third embodiments;

FIG. 5 is a top plan view of the separated lower assembly of the first and third embodiments;

FIG. 6 is a front, left perspective view of a second and fourth embodiments of an electrical switch showing my new design;

FIG. 7 is an exploded, front, left perspective view of the second and fourth embodiments;

FIG. 8 is a top plan view of the second and fourth embodiments;

FIG. 9 is a top plan view of the separated upper assembly of the second and fourth embodiments;

FIG. 10 is a top plan view of the separated lower assembly of the second and fourth embodiments;

FIG. 11 is a left side view for all embodiments, the right side view being identical thereto;

FIG. 12 is a left side view of the separated upper assembly for second and fourth embodiments, the right side view being identical thereto;

FIG. 13 is a left side view of the separated lower assembly for second and fourth embodiments, the right side view being identical thereto;

FIG. 14 is a front elevational view of the separated upper assembly for second and fourth embodiments, the rear view being identical thereto;

FIG. 15 is a front elevational view of the separated lower assembly for second and fourth embodiments, the rear view being identical thereto;

FIG. 16 is a bottom, left perspective view for first and second embodiments;

FIG. 17 is an exploded bottom, left perspective view for first and second embodiments;

FIG. 18 is a bottom plan view of the separated upper assembly for first and second embodiments;

FIG. 19 is a bottom plan view of the lower assembly for first and second embodiments;

FIG. 20 is a bottom, left perspective view of third and fourth embodiments;

FIG. 21 is an exploded bottom, left perspective view of third and fourth embodiments; and,

FIG. 22 is a bottom plan view of the separated lower assembly for third and fourth embodiments.
